UNITED STATES PATENT OFFICE.

ELI CAMPANARI, OF NEW YORK, N. Y.

CAR-FENDER.

No. 807,152.

Specification of Letters Patent.

Patented Dec. 12, 1905.

Application filed August 11, 1905. Serial No. 273,752.

To all whom it may concern:

Be it known that I, ELI CAMPANARI, a citizen of the United States, and a resident of the city of New York, borough of Brooklyn, in 5 the county of Kings and State of New York, have invented a new and Improved Car-Fender, of which the following is a full, clear, and exact description.

This invention relates to improvements in 10 street-railway car-fenders, the object being to provide a fender so constructed that when not required for use it may be easily and conveniently folded against the dashboard of the car by the motorman without his getting off 15 the car, and, further, to so construct the parts that the fender may be attached to either end of the car.

I will describe a car-fender embodying my 20 invention and then point out the novel features in the appended claims.

Reference is to be had to the accompanying 25 drawings, forming a part of this specification, in which similar characters of reference indicate corresponding parts in all the figures.

Figure 1 is a front elevation of a car-fender embodying my invention, showing the same as down. Fig. 2 is a side elevation thereof. Fig. 3 is a front view showing the fender as 30 folded. Fig. 4 is a side view thereof, and Fig. 5 is a detail illustrating the means for securing the fender-frame to a car.

The fender comprises a main frame 1, designed to be detachably secured to the front 35 of the car-dashboard. As here shown, the side rails of the frame 1 have reduced lower ends 2 for engaging in openings in hangers 3, depending from the sill of the car. As clearly shown in the drawings, the hangers each have 40 two openings or socket members on different vertical planes, so that the frame may be raised or lowered to accommodate the fender to the height of the car from the rails. On the upper cross-bar 4 of the main frame is 45 a lug 5, having a threaded extension 6, on which is a thumb-nut 7. This extension when the frame is in position is designed to be engaged by a hook 8, pivoted on the rail 9 of the dashboard. When the said 50 hook is engaging with the threaded extension, it is clamped by means of the thumb-nut 7.

The fender-frame consists of an upper section 10 and a lower section 11, these sections being pivotally connected together, so that 55 the lower section may fold upon the upper section, as indicated in Figs. 3 and 4, and con-

nected to these frame-sections is the netting 12. A bar 13 at the upper end of the fender-frame has bearings in the side bars of the main frame 1, and mounted to swing on the 60 lower cross-bar 14 of the main frame is a supporting-arm 15, having a slot 16 for receiving a pin 17, extended from a side bar of the lower frame member 11. Connected to the opposite side bar of said lower frame mem- 65 ber is a toggle-link, consisting of a lower section 18 and an upper section 19, the said upper section being pivoted at about its center to the side rail of the frame member 10, and at its upper end the said toggle-link mem- 70 ber 19 has pivotal connection with an arm 20, pivoted to the side rail of the main frame 1.

Attached to the frame 20 is a segment- 75 plate 21, which is arranged to slide in a guide 22 on the side bar or rail of the main frame 1, as clearly indicated in the drawings. This segment-plate 21 is provided with two 80 handles 22 23, one arranged below the other, so that one or the other will be in a convenient position, depending upon the arrangement of the main frame in the hangers 3.

When the fender is in its lower position, it is supported at one side by the link-and-arm construction above described and at the other side by means of a chain 24, having a ring 25 85 at its upper end for engaging with a pin 26 on the bar 4. When the fender is in its folded or elevated position, it is held by means of a hook 27, mounted on the bar 4, and engages with a lug 28 on the upper member 19 of the 90 toggle-link.

A car-fender made in accordance with my 95 invention may be of very light construction, and therefore readily carried from one end of the car to the other, and through the medium of the toggle-links and connections with the segment-plate it may be readily raised or lowered by a motorman without his getting off the car.

Having thus described my invention, I 100 claim as new and desire to secure by Letters Patent—

1. A car-fender comprising a main frame, a fender-frame consisting of two hinged sections having swinging connection with the 105 main frame, an arm mounted to swing on the main frame, toggle-link connections between said arm and the lower members of the fender-frame, a segment-plate having pivotal connection with said arm, and a guide on the 110 main frame through which said segment-plate may move.

2. In a car-fender, a main frame, hangers on the car in which the lower ends of the side rails of the main frame removably engage, a hook on the dashboard of the car, a threaded extension on the top rail of the main frame with which said hook is designed to engage, a clamping-nut on said extension, and a fender attached to the main frame.

3. A car-fender comprising a main frame, 10 a fender-frame consisting of upper and lower pivotally-connected sections, the upper member being pivotally connected to the side bars of the main frame, a slotted guide-arm pivoted to one of said side bars of the main 15 frame, a pin extended from the lower section of the fender-frame into the slot of said arm, an arm mounted to swing on the main frame, a toggle-link connection between said arm and the lower member of the fender-frame, a 20 segment-plate pivoted to said arm, and a guide on the main frame in which said segment-plate may slide.

4. In a car-fender, a main frame, hangers

secured to a car-sill and each having socket members arranged at different vertical planes 25 for receiving the lower ends of the main frame, means for detachably connecting the upper portion of the main frame with the rail of the car-dashboard, and a fender mounted on the main frame. 30

5. A car-fender comprising a main frame, a foldable fender mounted on the main frame, an arm having swinging connection with the main frame, a toggle-link connection between said arm and the fender-frame, a lug 35 on the upper member of said toggle-link, and a hook on the main frame for engaging with said lug.

In testimony whereof I have signed my name to this specification in the presence of 40 two subscribing witnesses.

ELI CAMPANARI.
